poration

Application January 16, 1933, Serial No. 652,090

16 Claims. (Cl. 83—73)

In the laying of concrete, as for example in road building operations, it is common practice to subject the aggregates to mixing operations in transit between a central mixing plant and the point of the concrete laying operations. For this purpose the aggregates are customarily charged into mixing trucks, which stir and agitate the aggregates within a rotating drum until the proper degree of mixing of the aggregates is obtained. Frequently the drums are of a type which mix the aggregates upon rotation of the drum in one direction and then move the aggregates after mixing the same to discharge the said aggregates from the drum when the point of discharge has been reached. This discharging action is obtained by reversing the direction of rotation of the drum.

For the accomplishment of the proper mixing action, mechanism has been devised which will time the mixing action of the drum in such a manner as to prevent the drum being discharged until the required number of mixing revolutions of the drum have been accomplished. This mechanism includes, in general, instrumentalities which are set at the beginning of the mixing period, rendering inoperative the discharge devices of the drum simultaneously with the setting of the timing instrumentalities, these latter recording the number of turns made by the mixing drum during the mixing period, and then, through actuation of suitable signalling devices, indicating to an operator the completion of the predetermined mixing period, and rendering the drum in condition whereby the mixing contents thereof may be discharged.

The present invention relates in general to mechanism of this aforesaid general character, the invention dealing more specifically with improvements in the mechanism controlled by the timing or batchmeter device for locking the discharge of the drum which prevents opening thereof until the predetermined mixing operation has been completed. Upon expiration of this predetermined mixing operation, the drum is enabled to be discharged, the batchmeter acting to indicate to an attendant that the mixing period has been completed. Furthermore, the present invention relates to mechanism actuating the batchmeter at the start of the mixing operation, means being provided for rendering the said batchmeter actuating mechanism inoperative as soon as the batchmeter is actuated, so that the actuation thereof will not be interfered with during the mixing period, and devices for restoring the said batchmeter actuating instrumentalities to operative condition when the direction of rotation of the drum is reversed for effecting the discharge of the drum.

The construction of the present invention utilizes a control mechanism or so-called "Batch-

meter", of the general type described in United States Patent No. 1,532,277 granted to H. A. Trester and dated April 7, 1925. The present invention, however, not only embraces the general system of apparatus described in the aforesaid Trester patent, but adapts the batchmeter of this patent to be used in connection with a truck type concrete mixer. There is provided a system of linkages which gives a positive control of the discharge of materials from the drum, the said linkages being actuated by instrumentalities set into operation by the setting of the batchmeter and released incident to reversal of rotation of the mixing drum upon completion of the mixing operation as indicated by the signal of the batchmeter advising the attendant of the completion of the mixing operation.

The present invention embraces instrumentalities whereby the batchmeter will not only be actuated automatically upon the start of the mixing operation, but wherein the actuating mechanism will be rendered inoperative as soon as the batchmeter starts to operate, so that during the mixing period there will be no interference with the operation of the batchmeter. When the signal is given that the mixing period is completed, the drum is stopped and rotated in the opposite direction to effect the discharge of the drum; and the invention embraces instrumentalities which automatically restore the batchmeter actuating mechanism into operative position, thereby rendering the mechanism immediately operative for the next mixing operation.

The instrumentalities of this invention are of such construction as will be rendered operative upon reversal of rotation of the drum, so as to enable the discharge of the drum to be effected. In general the instrumentalities embrace a lever operatively connected with the batchmeter setting mechanism, which lever is integral with a gear and which is engaged by a retractable abutment member mounted on the drum. The gear carries a rack which moves into the path of travel of the abutment member simultaneously with the setting of the batchmeter, and serves to retract the abutment member out of engagement with the lever during subsequent rotations of the drum. The mechanism also includes means for releasing the abutment member from its retracted position when the direction of rotation of the drum is reversed, so that the abutment member returns to its original position and is enabled, therefore, to reset the batchmeter at the start of the next mixing period.

This mechanism avoids the objection inherent in proposed devices of the prior art which have been universally open to the objection that it has not been possible to avoid engagement between the abutment and the mechanism cooperating therewith at each successive rotation of the

drum; and so far as is known, there have been no means proposed whereby the batchmeter may be initially set through the use of abutment instrumentalities mounted on the drum, which instrumentalities are then rendered inoperative during the remainder of the mixing period.

In accordance with the present invention, the objection just indicated is completely removed and a highly simplified yet fully operative control system has been devised.

The above indicated objects of the invention, together with other objects and advantages inherent in the present construction which will become apparent as the description proceeds, are very satisfactorily fulfilled by the present construction, the details of which will be more fully set forth hereinafter.

Figure 1 is a side view of a concrete mixer truck of a standard construction provided with the improved mechanism of the present invention.

Figure 2 is a fragmentary view of the front end of the mixing drum showing the details of construction of the improved mechanism, with the batchmeter ready to be set for registering the mixing period of the drum.

Figure 3 is a view similar to Figure 2, but showing the arrangement of the parts upon setting of the batchmeter.

Figure 4 is a fragmentary top view showing the means for locking the discharge of the drum against opening during the mixing period.

Figure 5 is a perspective view showing the details of a spring employed in holding the abutment member shown in Figure 3, in retracted position.

Fig. 6 is a detailed perspective view of a lever employed in releasing the spring member illustrated in Fig. 5.

Referring more particularly to the drawings, A represents a standard type mixing truck for concrete having the usual rotating mixing drum B mounted thereon. Adjacent the mixing drum B is a water tank C, mounted on the bracket D which carries also the batchmeter E for indicating the mixing periods of the drum. This batchmeter is of the type described and claimed in the Trester Patent No. 1,532,277, aforesaid.

The mixing drum B is desirably of the type which rotates in one direction for the mixing operation, the direction of rotation being reversed for the discharge of the aggregates from the drum, the discharge being accomplished by means of a discharge opening on the end of the drum, which opening is controlled by a closure F.

The direction of rotation of the drum is controlled through clutch instrumentalities actuated by a lever G, which lever is shiftable from neutral to mixing and discharge directions of rotation of the drum, respectively.

The above features are standard practice, and form no part of the present invention. They need not be described in detail therefore. Also, the construction and operation of the batchmeter E is well known, being set forth and described in detail in the Trester patent previously referred to.

It will be understood that one of the primary purposes of the batchmeter E is to prevent the opening of the closure F during the mixing period when the aggregates charged into the mixing drum are being mixed together to form a concrete of proper consistency. It is desirable that the batchmeter E be set responsive to rotation of the drum so as to indicate to an attendant when the predetermined number of revolutions of the

drum set upon for the mixing period have actually been accomplished.

It is not deemed necessary to describe in any detail the internal mechanism of the batchmeter, as this is clearly set forth in the Trester patent mentioned above. However, suitable drive means for the batchmeter must be provided, which as illustrated, comprise a shaft H terminating in a beveled gear I which meshes with a second bevelled gear J mounted on the end of a shaft K. This shaft K terminates in a gear L which meshes with the usual ring gear of a mixing drum.

As in the aforesaid Trester patent, the batchmeter is set through the instrumentality of a rod 1, which extends completely through the batchmeter housing and terminates in a slotted end 2 in which is fitted a pin 3, which is in turn received in a slot 4 in the arm 5 of a bell crank which is pivotally mounted at 6 to a bracket 6a which is in turn mounted on a bracket 6b, the latter being secured to the bracket D and carrying the batchmeter E. The other arm 7 of the bell crank is connected to a rod 9a, which rod is connected to a second bell crank 5a. This bell crank in turn is connected to a rod 8, which runs longitudinally of the drum B, and serves to actuate a third bell crank 9, which is pivotally mounted at 10 to a bracket 11. This bracket is provided with a bearing 12 through which extends the rod 13, interconnected with a bell crank 9, which rod is adapted to be moved into engagement with the closure F upon setting the batchmeter through the actuation of the rod 1.

The mechanism for setting the batchmeter will now be described. It will be seen from the drawings that the upper end of the rod 1 is inserted in the slot 14 located in the end of an arm of a bell crank 15, which is fixedly secured at 16 to a gear 17. This bell crank and gear are substantially enclosed in a housing 18 which is mounted by brackets 19 on the forward ring bearing 20 of the mixing drum. The other arm of the bell crank extends through the housing, as indicated at 21, and is adapted to be engaged by an abutment member 22 mounted on the front end of the drum. This abutment member 22 is held in place by brackets 23, the member 22 being slidably behind these brackets for reasons which will be hereinafter more clearly explained, and is provided with a retaining pin 24 which prevents the abutment member 22 from becoming displaced from behind these brackets. A spring 25 normally urges the abutment member 22 in extended position.

It will be seen that as the drum rotates in the direction of the full arrow in Figure 2, the abutment member 22 will engage the arm 21 of the bell crank 15 and turn the bell crank together with the gear 17 until the bell crank assumes the dotted line position in Figure 2, or the full line position in Figure 3. This in turn lifts the rod 1, and sets the batchmeter for recording the start of the mixing period of the drum, incidentally shifting the rod 13 so as to prevent opening the door F during the said mixing period. It will be seen, however, that at the completion of the mixing period, when the batchmeter is tripped, and counter-rotation of the drum is started for the discharge of the said drum, there would be no means, in accordance with the mechanism described, through which engagement of the abutment 22 with the arm 21 of the bell crank 15 would be avoided, with consequent damage to, or destruction of, the described mechanism. Instrumentalities, which will be hereinafter de-

scribed in detail, must be provided, accordingly, for eliminating such difficulty.

Furthermore, the batchmeter is arranged to automatically release at the expiration of a predetermined time. When this occurs, the drum is supposed to be discharged, but, because of the circumstances often present during conditions of operation, the drum may not be reversed until one or more additional revolutions of the drum have been made, there being no means customarily provided for automatically stopping the rotation of the drum incident to the release of the batchmeter. However, simultaneously with this release in the construction shown, the arm 21 would be immediately shifted from the dotted line position of Figure 3 to the full line position of Figure 2, so that it would again come into the path of the abutment 22 and the batchmeter will be reset for continued mixing by the engagement of the abutment 22 by virtue of the aforesaid continued rotation of the mixing drum. Under such conditions, a mixing period would commence again, and the operativeness of the mechanism would be destroyed, since, as long as the batchmeter is operating, discharge of the drum is impossible. Furthermore, the tripping of the batchmeter might occur at such a time that engagement with the abutment 22 would be instantaneous with the return of the arm 21, and the batchmeter might be reset without even giving the intended signal that the mixing time is complete.

To prevent this resetting of the batchmeter, there is mounted within the housing 18 a rack 26, having teeth 27 intermeshing with the teeth of the gear 17. The rack 26 is slotted as at 28, and into this slot are fitted guide pins 29. It will therefore be seen that when the bell crank 15 is moved to set the batchmeter, the corresponding movement of the gear 17 will extend the rack 26 into the path of movement of the abutment 22 as the drum rotates. This will be clearly seen from the position of the parts in Figure 3.

The end of the rack 26 is cut at a sloping angle, as indicated at 30, the resulting surface having a cam action on the abutment member 22. As the end of the abutment member engages the inclined surface 30 of the rack 26, the abutment member 22 will be positioned backwardly against the tension of the spring 25 until the abutment member 22 clears the end 30 of the rack 26. For securing the abutment member 22 in this position, it is provided with a notch 31 into which snaps a spring 32 suitably mounted on the drum adjacent the abutment 22, and the abutment member is thereby held in retracted position. In this position, the abutment member 22 is moved well out of any path of engagement with the bell crank 15.

It is necessary, however, that the batchmeter be reset during the discharging operation.

In order to render the member 22 available for resetting the batchmeter at the proper time, instrumentalities must be provided for releasing the member from its retracted position. This mechanism will now be described. Upon the bracket D is positioned a supporting bracket 33, upon which is mounted a bell crank 34. The bell crank 34 is pivoted to the bracket 33 at the point 35. A longer arm 36 of the bell crank being engaged by a spring 37 suitably secured to the support D, is provided with a lateral extension 38 which is adapted to engage a lateral extension 39 on the spring 32. Between the bracket 33 and a shorter arm 40 of the bell crank

34, there is positioned the spring 41, held in position by a lug 42 on the bracket 33. The relative strength between the springs 37 and 41 is such that when the drum is rotating during the mixing period, engagement of the extension 39 with the arm 36 will depress the arm 36 against the tension of the spring 37 sufficiently to allow the lever 34 to turn on its pivot point 35 to allow the extension 39 to pass by the lever upon each rotation of the drum.

When the drum is rotated in the opposite direction, the extension 39 will strike the lever 34 in the opposite direction, so that the spring 41 will be compressed by the engagement between the extension member 39 and the lever 34. The extension member 39 operates the arm 36 so as to compress the spring 32 and thereby is enabled to pass the arm 36; and since the strength of the spring 41 is greater than the strength of the spring 32, the latter will be lifted out of engagement with the notch 31 and the abutment 22 snapped into its extended position by the action of spring 25. This returns the abutment 22 into the path of contact with the arm 21 of the bell crank 15 of the batchmeter. To enable the abutment 22 to freely pass this arm 21, the end of the arm is desirably made in the form of a section 43 pivotally secured at 44 to the arm 21 so that the section 43 will turn on the pivot 44 upon engagement with the abutment 22 upon rotation of the drum in the direction of the dotted arrow in Figure 3 while being rigidly braced by the arm 21 upon engagement with the abutment member 22 as the latter strikes the section 43 during rotation of the drum in its mixing direction indicated by the arrow M in Figure 2. This resets the batchmeter, and it will be understood that when the abutment 22 continues to move in response to the mixing rotation of the drum, extension 39 engages the arm 36 of the bell crank 40 34 to depress the arm with an attendant expansion of spring 41 sufficiently to allow extension 39 to pass by.

It will therefore be seen that the mechanism provided by this invention enables the automatic setting of the batchmeter after each mixing and discharging of the aggregates, the operation of the batchmeter not being interfered with in any way by rotation of the drum subsequent to the setting of the batchmeter.

Having thus described my invention, what I claim as new and desire to secure by Letters Patent of the United States, is—

1. A mechanism of the character described, comprising, in combination, a mixing drum combined with a batchmeter of the continuous driven type for indicating completion of mixing operations in the drum, mechanism for controlling the direction of rotation of the drum, instrumentalities for setting the batchmeter at intervals responsive to the direction of rotation of the drum, and mechanism operable by setting of the batchmeter for rendering the said instrumentalities inoperative after setting of the batchmeter, the said instrumentalities comprising an abutment member movably mounted on the drum and a lever connected with the batchmeter and adapted to cooperate with the said abutment member, the abutment member being adapted to be moved out from the path of engagement with the lever after the batchmeter has been set.

2. A mechanism of the character described, comprising, in combination, a mixing drum combined with a batchmeter of the continuous driven type for indicating completion of mixing opera-

- tions in the drum, mechanism for controlling the direction of rotation of the drum, instrumentalities for setting the batchmeter at predetermined intervals responsive to the direction of rotation of the drum and comprising an abutment member carried by the drum, and a lever cooperating with the abutment member and connected to the batchmeter, and mechanism operable by setting of the batchmeter for rendering the said abutment member inoperative after setting of the batchmeter, the said mechanism including means extensible into the path of rotation of the abutment member and devices operable by the setting of the batchmeter for extending the said means into the path of rotation of the abutment member, whereby the latter is moved into inoperative position upon impact with the said extensible means.
3. Mechanism of the character described comprising, in combination, a mixing drum combined with a batchmeter for indicating completion of mixing operations on the drum, instrumentalities for setting the batchmeter for timing operation upon rotation of the drum in one direction, mechanism for rendering the said instrumentalities inoperative after setting of the batchmeter, and devices for restoring the said instrumentalities to operative condition upon rotation of the drum in another direction.
4. Mechanism of the character described, comprising, in combination, a mixing drum combined with a batchmeter for indicating completion of mixing operations in the drum, instrumentalities for actuating the batchmeter responsive to rotation of the drum in one direction, and mechanism operable by setting of the batchmeter for rendering the said instrumentalities inoperative after setting of the batchmeter, the said instrumentalities comprising an abutment member slidably mounted on the drum and adapted to be moved away from the path of engagement with the batchmeter setting mechanism after the batchmeter has once been set, means for securing the said abutment member in its inoperative position, and devices for restoring the said abutment member to operative position upon rotation of the drum in another direction.
5. A mechanism of the character described, comprising, in combination, a mixing drum combined with a batchmeter for indicating completion of mixing operations in the drum, instrumentalities for actuating the batchmeter at predetermined intervals responsive to rotation of the drum, the said instrumentalities including a lever operatively associated with the said batchmeter, an abutment member mounted on the drum for engagement of the said lever as the drum rotates, whereby actuation of the lever by the said abutment member results in setting of the batchmeter at the start of the mixing period for aggregates contained in the drum, and mechanism operable by setting of the batchmeter for rendering the said instrumentalities inoperative incident to the setting of the said batchmeter, the said instrumentalities comprising a gear movable responsive to the setting of the batchmeter, and a rack in engagement with the said gear, the said rack being movable to engagement with the said abutment member responsive to movement of the gear incident to setting of the batchmeter.
6. Mechanism of the character described, comprising, in combination, a mixing drum combined with a batchmeter for indicating completion of mixing operations in the drum, instrumentalities for actuating the batchmeter at predetermined

intervals responsive to rotation of the drum, mechanism operable by setting of the batchmeter for rendering the said instrumentalities inoperative incident to setting the batchmeter, and devices for restoring the said instrumentalities to operative position at a predetermined time interval upon reversal of direction of rotation of the drum, the said devices including a lever mounted adjacent the drum and enabled to be tripped by the said instrumentalities upon rotation of the drum in one direction, while being adapted to act upon the said instrumentalities to release the same upon engagement therewith on reversal of rotation of the drum.

7. A mechanism of the character described, comprising, in combination, a mixing drum combined with a batchmeter for indicating completion of mixing operations in the drum, instrumentalities for actuating the batchmeter at predetermined intervals responsive to rotation of the drum, and mechanism for rendering the said instrumentalities inoperative incident to setting the batchmeter, the said mechanism comprising a rack extensible into the line of travel of the said instrumentalities, devices for moving the said rack into the said path of travel of the instrumentalities incident to setting the batchmeter, the said rack being provided with a surface adapted to be engaged by the said instrumentalities, whereby the latter will be retracted responsive to continued rotation of the drum, and means for holding the said instrumentalities in retracted position.

8. A mechanism of the character described, comprising, in combination, a mixing drum combined with a batchmeter for indicating completion of mixing operations of the drum, instrumentalities for actuating the batchmeter at predetermined intervals responsive to rotations of the drum, the said instrumentalities comprising a lever operatively connected with the said batchmeter, an abutment member mounted on the drum and adapted to engage the lever upon rotation of the drum to thereby set the said batchmeter, and mechanism for rendering the said abutment member inoperative incident to setting the batchmeter, the said mechanism comprising a rack member adapted to be extended into the path of movement of the said abutment member, the said rack member being provided with a surface adapted to retract the said abutment member from engagement therewith as the abutment member passes by the rack, and mechanism for actuating the said rack responsive to operations of the said batchmeter.

9. An apparatus of the character described, comprising, in combination, a mixing drum, a batchmeter for the drum, instrumentalities on the drum for setting the batchmeter responsive to rotation of the drum and including cooperating guide brackets mounted on the drum, an abutment member positioned beneath the guide brackets and movable relatively thereto from extended to retracted position, and contrarily, a lever engageable by the said abutment member and operatively connected with the batchmeter, whereby engagement between the abutment member and lever will set the batchmeter, an extensible rack member movable toward and away from the said abutment member responsive to corresponding actuation of the batchmeter, the said rack member having a cam acting surface adapted to be engaged by the abutment member for retracting the latter out of engagement with the rack member, instrumentalities for moving the rack mem- 75

ber responsive to corresponding operation of the batchmeter, spring devices for holding the abutment member in withdrawn position as the drum revolves in a mixing direction, and means for releasing the spring devices for enabling the abutment member to return to extended position upon reversal of direction of rotation of the drum.

10. An apparatus of the character described, comprising, in combination, a mixing drum, a batchmeter for the drum, instrumentalities on the drum for setting the batchmeter responsive to rotation of the drum and including cooperating guide brackets mounted on the drum, an abutment member positioned beneath the guide brackets and movable relatively thereto from extended to retracted position, and contrarily, a lever engageable by the said abutment member and operatively connected with the batchmeter, whereby engagement between the abutment member and lever will set the batchmeter, an extensible rack member movable toward and away from the said abutment member responsive to corresponding actuation of the batchmeter, the said rack member having a cam acting surface adapted to be engaged by the abutment member for retracting the latter out of engagement with the rack member, instrumentalities for moving the rack member responsive to corresponding operation of the batchmeter, spring devices for holding the abutment member in withdrawn position as the drum revolves in a mixing direction, and means for releasing the spring devices for enabling the abutment member to return to extended position upon reversal of direction of rotation of the drum, the said means comprising a trip device positioned in the path of movement of the abutment member and having means for engaging the said spring devices to release the latter for enabling the abutment member to return to extended position upon the said reversal of direction of rotation of the drum, the abutment member tripping the said trip device for passage thereby during mixing rotation of the drum.

11. A mechanism of the character described, comprising, in combination, a mixing drum provided with a batchmeter for indicating completion of mixing operations in the drum, instrumentalities for actuating the batchmeter at predetermined intervals responsive to rotations of the drum in mixing direction, mechanism for rendering the said instrumentalities inoperative incident to actuation of the batchmeter, and means for restoring the said batchmeter actuating instrumentalities to operative condition responsive to reversal of direction of rotation of the drum for discharging the same.

12. An apparatus of the character described, comprising, in combination, a mixing drum, a batchmeter for the drum, instrumentalities on the drum for actuating the batchmeter responsive to rotation of the drum in mixing direction, the said instrumentalities comprising a lever operatively connected with the batchmeter, an abutment member mounted on the drum and adapted to engage the lever upon rotation of the drum in mixing direction to thereby actuate the said batchmeter, mechanism for rendering the said abutment member inoperative upon actuation of the batchmeter, the said mechanism comprising a rack member adapted to be extended into the path of movement of the abutment member, the said rack member being provided with means for moving the abutment member from engagement

therewith and into inoperative position as the abutment member passes by the rack, and mechanism for releasing the abutment member for restoring the same to operative position responsive to reversal of direction of the drum for discharge thereof.

13. In a device of the character described, in combination with a batchmeter of the continuously driven type, including driven mechanism and instrumentalities for setting the driven mechanism for indicating completion of mixing operations, a mixing drum, driving means on the drum for driving the driven mechanism of the batchmeter upon rotation of the drum, of actuating mechanism mounted on said drum and adapted to engage with the instrumentalities for setting the driven mechanism of the batchmeter upon rotation of the drum in mixing direction to start the batchmeter mechanism for indicating completion of mixing operations in the drum, and instrumentalities for rendering the actuating mechanism inoperative when the indicating operation of the driven mechanism of the batchmeter has once been started.

14. An apparatus of the character described, comprising, in combination, a mixing drum, a batchmeter for the drum, instrumentalities for setting the batchmeter responsive to rotation of the drum in one direction, including a movable abutment member on the drum and a lever on the batchmeter adapted to be engaged by the abutment member, guide brackets on the drum for movably securing the abutment member to the drum, instrumentalities actuated by setting of the batchmeter for moving the abutment member out of engagement with the lever after the batchmeter has once been set, holding means for securing the abutment member in a retracted position and out of engagement with the said lever, and devices engageable with the said holding means upon rotation of the drum in another direction to restore the abutment member to its extended position.

15. A mechanism of the character described, comprising, in combination, a mixing drum combined with a batchmeter of the continuously driven type for indicating completion of mixing operations in the drum, mechanism for controlling the direction of rotation of the drum, instrumentalities for setting the batchmeter for mixing completion indicating action thereof responsive to rotation of the drum in one direction, and mechanism operable by setting of the batchmeter for rendering the said instrumentalities inoperative after setting of the batchmeter.

16. A mechanism of the character described, comprising, in combination, a mixing drum combined with a batchmeter of the continuously driven type for indicating completion of mixing operations in the drum, mechanism for controlling the direction of rotation of the drum, instrumentalities for setting the batchmeter for mixing completion indicating action thereof responsive to rotation of the drum in one direction, mechanism operable by setting of the batchmeter for rendering the said instrumentalities inoperative after setting of the batchmeter until the direction of rotation of the drum is reversed, and mechanism coacting with the last mentioned mechanism to restore said setting instrumentalities to operative position upon reversing the direction of rotation of the drum.
